ATTORNEY

UNITED STATES PATENT OFFICE.

CHARLES J. PAULSON, OF BROOKLYN, NEW YORK.

SNAP-FASTENING.

1,262,244.

Specification of Letters Patent. Patented Apr. 9, 1913.

Application filed June 5, 1917. Serial No. 172,948.

To all whom it may concern:

Be it known that CHARLES J. PAULSON, a subject of the King of Sweden, residing at the borough of Brooklyn, in the county 5 of Kings and State of New York, has invented a new and useful Improvement in Snap-Fastenings, of which the following is a specification.

This invention relates to fastenings for 10 garments and other purposes, and my improvement refers particularly to that class of these devices known as snap fasteners, wherein one member, as a male portion, engages a female portion of another member, 15 and is frictionally or tensionally retained therein.

Briefly, my invention consists of a female member composed of a plate of spring-like material, such as metal, said plate being 20 folded upon itself and having aligned orifices, the orifice in one of the folded parts being of sufficient diameter to freely receive the engaging portion of the male member, and the other folded part, which is located at 25 the rear of the first named folded part, having an orifice which is of slightly less diameter than the engaging portion of the male member. The part having the smaller orifice is so devised that said orifice may be expanded under the application of pressure 30 from the entering portion of the male member, and also capable of resuming its normal contracted form to grip said engaging portion.

To this end, the material of that part of the female member having the smaller orifice, may be slit or separated so as to accord to the orifice the properties of expanding and contracting.

There is thus set up in the female member 40 a support or containment for the shank of a button or male fastening member of usual character, the head of which latter is enabled to enter freely through the larger 45 orifice in the one part of the female member, and to, by pressure, be forced into a locking engagement with the smaller orifice in the other part of the female member.

By the means described, the unslotted part 50 of the female member affords a rigid bearing or socket which lends strength to the fastening and serves as a base or support for the more flexible and actually engaging fastening element, which, as stated, is in the 55 form of a slotted or separated rearward part of the folded over plate and provided with

an expandible and contractible smaller orifice.

Other features and advantages of my said invention will hereinafter appear. 60

In the drawing:

Figure 1 is a perspective view of a blank which constitutes the female member of my improved fastening.

Fig. 2 is a cross sectional view of said 65 blank as folded and formed into operative condition.

Fig. 3 is a similar view, also showing a male member engaged with said female member, and 70

Fig. 4 is a plan view of the male member.

In carrying out my invention, for the production of the female fastening member, I take a strip of spring-like material, like half hard brass, for example, as indicated 75 in Fig. 1 and provide it, as by stamping, with the orifices 1, 2, then folding the strip upon itself, as over the line 3, to aline the axes of said orifices.

The part 4, having the larger orifice 1, 80 comprises the front of the female fastening member, and the part 5, having the smaller orifice 2, comprises the rear of said member. Said part 5 is slotted or slotted, as at 6, the slits or slots extending from the orifice 2, to 85 render elastic or yielding that portion of the material of part 5 which borders on the perimeter of slot 2, whereby pressure applied at the perimeter of said orifice 2, as under the attack of a button or male member of a 90 fastening, will cause said orifice 2 to expand for the passage of said male member; said orifice 2 then contracting to tensionally retain said male member.

In Fig. 3 I have shown an example of 95 male fastening member having base 6, head 7 and shank 8. Its head 7 may be of conventional, rounded form, with cross-sectional diameter less than the interior diameter of orifice 1, to enter freely therethrough, 100 but of greater diameter than the interior diameter of orifice 2, so that its way must be forced through the latter.

It should be noted that the entrance to the orifice 1 may be sunk in a concave depression formed in the part 4 of the female member, and that a concentric shoulder may surround said depression, to thus allow for the aforesaid conformation, while maintaining desirable compactness in said 110 female member.

The contour of the male member base sur-

face opposed to the female member may conform to the contour of the latter, in order that the two members may fit snugly together when in engaged relation.

5 In the operation of this invention, the two members are separately attached to the parts of a garment or other article which they are to fasten, and then the head 7 of the male member may be freely introduced to 10 into orifice 1, and, under pressure, caused to snap through the orifice 2, whereby the shank 8 will be lodged in both orifices and the head 7 will be tensionally held against withdrawal through its engagement with the 15 rear edge of orifice 2.

Disengagement of the members is effected in the manner usual with these devices, by the application of pressure to overcome the tensional hold of the part 5, causing the 20 orifice 2 to expand and thus permitting the withdrawal of head 7.

I claim:

1. A female member for snap fastening devices, comprising superposed plate portions having alined orifices of different 25 diameters, the larger orifice being of a diameter to freely receive the head of a

male portion, and the smaller orifice being of a diameter less than that of such head, the material of the plate portion with the 30 smaller orifice being of spring-like character, and having slits communicating therewith, whereby said orifice may be expanded under pressure applied by such head, to receive and tensionally retain the latter. 35

2. In a snap fastening device comprising a male member having a head and shank, the combination of a female member composed of a folded plate, whose portions are in superposed relation, with alined reception 40 orifices for said head, the orifice in the rear portion being smaller than said head and having entering slits, whereby said orifice may be expanded under pressure applied by said head, to receive and tensionally retain 45 the latter.

In testimony whereof, he has signed his name to this specification in the presence of two subscribing witnesses, this first day of June, 1917.

CHARLES J. PAULSON.
